ICE SCRAPER

Alan G. Engstrom, Erie, Pa., assignor to Light Metal Products, Erie, Pa., a proprietorship of Pennsylvania

Application January 5, 1954, Serial No. 28,372

Term of patent 14 years

(Cl. D9—6)

To all whom it may concern:

Be it known that I, Alan G. Engstrom, have invented a new, original, and ornamental Design for Ice Scraper, of which the following is a specification, reference being had to the accompanying drawing, forming a part thereof.

Fig. 1 is a top plan view of the ice scraper, showing my new design.

Fig. 2 is a side view thereof.

Fig. 3 is a front view thereof.

The dominant features of the design are shown in full lines.

I claim:

The ornamental design for an ice scraper, as shown and described.
